UNITED STATES PATENT OFFICE

2,399,677

POWER SAW FOR CUTTING PLASTER CASTS

Frank E. Hood and James Edgar Hood,
Long Beach, Calif.

Application June 19, 1944, Serial No. 541,024

6 Claims.

(Cl. 30—124)

The present invention relates to improvements in power saws for cutting plaster casts, and its principal object is to provide a saw of the character described whereby a cast applied to a patient may be cut speedily for removal without any danger of injuring the skin of the patient.

A further object of the invention is to provide, in combination with a saw of the character described, a protecting foot adapted to ride between the skin of the patient and the cast so as to prevent the saw from coming in contact with the skin of the patient.

It is further proposed to provide an adjustable depth gauge for the saw whereby the saw's cutting action may be limited exactly to the thickness of the cast to be cut.

It is further proposed to provide means for carrying off the saw dust and to arrange the same in front of the saw immediately above the cast, and to make the same adjustable with the depth gauge.

And finally, we propose to provide a saw of the character described that is well balanced, easy to operate, quickly adjusted, and economic to manufacture.

Further objects and advantages of our invention will appear as the specification proceeds, and the novel features of our saw will be fully defined in the claims hereto appended.

The preferred form of our invention is illustrated in the accompanying drawing, in which:

Figure 1 shows a top plan view of our power saw;

Figure 2, an end view of the same; and

Figure 3, a fragmentary plan view of the end portion of the power saw with certain parts removed.

While we have shown only the preferred form of our invention, we wish to have it understood that various changes or modifications may be made within the scope of the claims hereto attached without departing from the spirit of the invention.

Referring to the drawing in detail, our power saw 1 comprises, in its principal features, a motor 2, a motor shaft 3 having a rotary saw 4 at one end and a fan 5 at the other end, a foot 6 underneath the saw, a depth gauge 7 adjacent the saw, a discharge conduit 8 for the dust, and a handle 9 whereby the whole device may be manipulated.

The motor housing has a tapered extension 10 coming to within close proximity of the saw and serving to furnish a bearing for the motor shaft near the saw. It also has a rectangular frame 11 projecting therefrom in the direction of the

saw and above the axis thereof, the frame comprising longitudinal bars 12 and 13 and two cross-members 14 and 15 disposed on opposite sides of the saw.

5 The frame 11 supports a hood 16 over the saw. It has a lateral extension 17, substantially in the plane of the saw, and this extension carries, with freedom of vertical adjustment, as by the screw and slot arrangement, shown at 18, a leg 19, which is curved toward the saw so as to support the foot 6 underneath the saw.

The foot 6 protects the skin of the patient for longitudinal cuts, but may be removed for vertical cuts into the plaster, when it is desired to cut a window into the cast. The adjustment takes care of saws of different sizes.

10 The front frame member 14, which is widened in its central portion, as at 20, carries the depth gauge 7 made in the form of a rectangular frame 21 having two vertical columns 22 slidable in the member 14, a top bar 23 and a bottom shoe 24 adaptable to ride on the plaster. The gauge may be adjusted by means of a screw 25 revolvably anchored in the frame member 14 and threaded 15 into the top bar 23.

15 The discharge tube 8 for the saw dust is arranged alongside of the motor housing and has a front elbow 26 leaning toward the lower edge of the saw so as to receive the saw dust. It is formed with a cut-out 27 in the edge facing the saw to provide better access for the saw dust. The front elbow is supported by an extension 28 of the gauge shoe 24 so as to be adjustable therewith.

20 20 The rear end of the discharge conduit connects, through an elbow 30, to the central intake 31 of a housing 32 for the fan 5. The tangential outlet 33 has a suitable dust receiving bag 34 secured thereto.

25 25 The elbow 30 is revolvable in the intake 31, as at 35 to allow of adjustment of the front end of the conduit by the raising and lowering of the gauge shoe 24, and the conduit 8 is extensible, as at 36, to allow of slight changes in the length of the conduit incident to the adjustment.

30 30 The frame 11 has a bracket 38 rising therefrom between the saw and the motor housing, and the rear member 39 of the bracket carries the handle 9 which is preferably made in the form of a standard hand-saw handle. The handle may be equipped with a trigger 41 for opening and closing the motor circuit and with a locking pin 42 for locking the trigger in circuit-closing position. 35 35 Suitable electrical connections have been indi-

cated at 43 and 44, but need no description since they are of conventional character.

In use, the operator suitably adjust the foot 6 and the gauge 1, which latter adjustment also places the front end of the conduit 8 into the proper position. The operator then lifts the device, gripping the handle with his right hand and the fan housing with his left hand, introduces the foot 6 underneath the plaster cast, pulls the trigger 41 for starting the motor and presses forward.

The saw will now cut through the plaster and the fabric of the cast, such as cloth, cotton or woolen padding, without any danger of injuring the skin of the patient.

The dust will be sucked into the conduit due to the action of the fan and will be discharged into the bag 34.

We claim:

1. A power saw for cutting plaster casts comprising a motor having a shaft projecting therefrom, a rotary saw on said shaft being spaced from the motor, a fixed member secured upon the motor and extending to within close proximity of the saw, and a gauge carried by the end of the fixed member adjacent the saw to limit the cutting depth of the latter, the gauge comprising a frame slideable in the fixed member and having a shoe adapted to ride on the surface of the cast to be cut, and threaded means for vertically adjusting the frame with respect to the fixed member.

2. A power saw for cutting plaster casts comprising a motor having a shaft projecting therefrom, a rotary saw mounted for operation by the shaft, a fixed member secured upon the motor and extending to within close proximity of the saw, a gauge carried by the fixed member for limiting the depth of the cut, and a discharge tube for catching the saw dust, the discharge tube having one end supported by the gauge.

3. A power saw for cutting plaster casts comprising a motor having a shaft projecting there-

from, a rotary saw mounted for operation by the shaft, a fixed member secured upon the motor and extending to within close proximity of the saw, a gauge, adjustable means on the fixed member for supporting the gauge, and a discharge tube for catching the saw dust, the discharge tube having one end supported by the gauge so as to be adjustable therewith.

4. A power saw for cutting plaster casts comprising a motor having a shaft projecting therefrom in opposite directions, a rotary saw on one end of the shaft, a fan on the other end of the shaft having a housing surrounding the same, a depth gauge for the saw, means for adjustably supporting the same, and a discharge conduit arranged alongside the housing, the discharge conduit having one end supported by the depth gauge in operative proximity to the saw for catching the saw dust so as to be adjustable with the gauge, and having its other end connected to the fan housing.

5. In a power saw for cutting plaster casts, a motor having a shaft projecting therefrom, a rotary saw mounted for operation by the shaft, an adjustable depth gauge for the saw, and a discharge conduit for the saw dust having its receiving end supported by the depth gauge so as to be adjustable therewith.

6. A power saw for cutting plaster casts comprising a motor having a shaft projecting therefrom, a rotary saw mounted for operation by the shaft, a fixed member secured upon the motor and extending to within close proximity of the saw, and a gauge carried by the fixed member adjacent the saw to limit the cutting depth of the latter, the gauge comprising a frame slideable in the fixed member and having a shoe adapted to ride on the surface of the cast to be cut, and means for vertically adjusting the frame with respect to the fixed member.
